UNITED STATES PATENT OFFICE

ALEXANDER M. KESSLER, OF BROOKLYN, NEW YORK, ASSIGNOR TO PREMIER SHOE COMPANY, INC., A CORPORATION OF NEW YORK

SHOE

Application filed December 11, 1928. Serial No. 325,161.

The invention relates to shoes, and also to processes or methods of making the same, and more particularly to improved forms and arrangements of linings, shank pieces and other parts thereof, and to methods of assembling the same with each other in the shoe, and has for one of its principal objects to provide a shoe which shall be of good appearance and wearing qualities, comfortable and beneficial to the foot, and simple, economical, and practicable in manufacture, and also to provide a satisfactory process or method for producing such a shoe. Further objects and advantages of the invention will be in part set forth in the following specification and in part will be obvious therefrom without being specifically pointed out, the same being realized and attained by means of the instrumentalities and combinations pointed out in the claim hereof.

In the manufacture of shoes as ordinarily carried out, it is often desired to provide support for the longitudinal arch of the foot in addition to that which is furnished by the ordinary shank piece, which may be accomplished either by some special form of shank piece or shank stiffener, or by the introduction of a separate "arch support". It has been found desirable to use shank pieces having various forms of lateral and upward extensions, but these have proved very unsatisfactory both in comfort and appearance, for the following reason: In the usual process of manufacture of a shoe, it is customary to attach the lower edges of both the outer member and the lining, together with a backing, if any, (the same being previously secured to each other near their upper edges), to the sole of the shoe around the entire outer edge thereof, and thereafter, and, if it be the type of shoe known as a turn shoe, after the same has been turned right side out, to insert the shank piece, within the shoe, upon the lining and in full view of anyone looking at the inside of the shoe. As in this case the upwardly extending arch-supporting portions at the sides of the shank piece are unsightly as well as that the more or less sharp edges thereof would be uncomfortable to the foot, it is usual to apply over these upwardly extend-

ing portions an auxiliary lining or covering, the same being attached, at its upper, forward and rear edges, to the main lining. This is very unsatisfactory, however, for the reason that it is not practicable to stitch said auxiliary linings in place, and the same are usually attached by glue or other adhesive, and in use the moisture of the foot, together with the constant friction to which the parts are subject, loosen the same and not only expose the uncomfortable and unsightly edges of the shank piece, but the auxiliary linings themselves tend to form an objectionable roll of material at each side of the shoe, and are thus worse than useless. Even before such loosening takes place, however, the patch-like auxiliary linings are not as pleasing in appearance as is desired in a shoe of high quality, or as is the case in a continuous lining. By my invention, however, a smooth and unbroken lining may be presented to the eye, satisfactorily and permanently covering and concealing the upwardly extending portions of the shank piece.

Another objection which is often found in the type of high-heeled shoe at present in extensive use by women, is that the same, even when provided with means for supporting the longitudinal arch of the foot, may nevertheless, on account of the high heel, throw the foot forward upon the ball thereof in such a manner as to bring an undue strain upon the same and weaken or tend to flatten down the transverse or metatarsal arch. Various means for remedying this defect have been tried, but many of the same have either proved inefficient for the purpose, or have been so uncomfortable that many wearers would discontinue the use thereof after a short time, or have been too heavy or clumsy for use in high-class shoes. By my invention, however, a simple and efficient device for this purpose may be produced.

With the above and other objects of the invention in view, the invention consists in the novel construction, arrangement and combination of various devices, elements and parts, as set forth in the claim hereof, certain embodiments thereof being illustrated in the accompanying drawings, and described

in this specification, and also in the process or method, as set forth in the claim hereof, one embodiment of which is fully described in this specification.

5 In the accompanying drawings, Fig. 1 is a top view of a partly completed shoe constructed according to one embodiment of my invention, a portion of the shank piece being raised and turned back to show the lining underneath;

10 Fig. 2 is a longitudinal sectional view taken along the line 2—2 of Fig. 1;

Fig. 3 is a top view of the shank piece alone;

15 Fig. 4 is a transverse sectional view taken on the line 4—4 of Fig. 3, looking toward the toe of the shoe;

Fig. 5 is a side view of Fig. 3, (a portion of the shank piece being broken away); and

20 Fig. 6 is a top view of one part of a modified form of shank piece.

In carrying the invention into effect in one of the embodiments thereof which have been selected for illustration in the accompanying drawings and for description in this specification, and in carrying out one form of my improved process, there is provided first a shoe sole of the usual or any suitable type, designated 10 in the drawings, and an upper

25 comprising an outer member 11 and a lining 12. These members of the upper may be of the usual or any suitable type, except that in the lower part of each side of the lining 12, at a point preferably near the front of the

30 heel, but which may be varied if desired, is a cut or slit extending upward to about the point at which, in the ordinary shoe, the lining would be stitched to the sole. If the shoe to be manufactured be a turn shoe, the said

35 sole 10 is first placed upon the last, and then the upper, comprising, as above mentioned, an outer member 11 and a lining 12, stitched together near their upper edges, is placed upon the last, the outer member 11 being inside,

40 that is, nearest to the last; in the ordinary practice, the next step would be to secure, by stitching or otherwise, the members 11 and 12 of the upper to the sole 10 around the entire edge thereof.

45 According to this embodiment of my invention, however, the outer member 11 of the upper is so secured, but that part of the lining 12 which, in the finished shoe, will be adjacent the shank piece (and as much more thereof as may be desired) is left unstitched and free at the lower edge thereof.

The shoe is then removed from the last, turned right side out, and such other operations performed as may be desired and 50 which form no part of the present invention, until the shoe is ready for the insertion of the shank piece, the lining being still, at least partially, unstitched at the lower edge.

Various forms of shank piece may be employed in connection with the improved form

of lining forming part of the present invention, but in Figs. 1 to 5 inclusive of the accompanying drawings there is shown a type thereof which in itself forms a part of the present invention, although not an essential part thereof, as my improved form of lining may be used with a different shank piece or my improved shank piece with a different lining.

55 Referring first more particularly to Fig. 3, it will be seen that the shank piece there illustrated, is formed of a single piece of leather or other suitable material, of sufficient thickness, strength and stiffness, for the purpose, and is split for a portion of its length so as to form a lower layer 15, an upper layer 16, and an unsplit heel portion 17. The lower layer 15 is cut in such shape as to provide two lateral portions, designated 18 and 19 respectively, which extend in an upward curve, the shaping and bending of the same being such that the curve toward the outside of the shoe begins comparatively near the outer edge and the extension 18 extends outwardly and upwardly but a short distance, whereas the curve toward the inside of the foot begins much further from that edge of the shank piece and the extension 19 on that side is much higher, in order to provide a firm support for the longitudinal arch of the foot, (see Figs. 4 and 5).

60 The upper layer or flap 16 is cut in approximately the same form as would be any ordinary shank piece which was not also an arch-support.

65 Referring now more particularly to Figs. 4 and 5, it will be seen that the unsplit heel portion 17 is somewhat thicker toward the inside of the shoe (see 9, Fig. 4), and that near the front end of the lower layer 15 of the shank piece, there is also a thicker portion of the leather at a point which will be near but not directly under the metatarsal arch of the foot when the shoe is worn, (see 8 Figs. 3 and 5).

70 A metal shank stiffener 7 of any suitable type may also be secured to the shank piece, but as the same forms no part of the present invention, it need not be here described in detail.

75 The shoe being, as above said, prepared for the insertion of the shank piece, the lower edges of that portion of the lining adjacent the heel of the shoe and behind the two cuts or slits above referred to, are glued or otherwise secured to the inside of the sole of the shoe, and the heel portion 17 of the shank piece laid upon the same and secured in place, the shank piece thus covering the edges of this part of the lining and forming a neat and well-appearing finish to this part of the shoe.

80 The portions of the lining forward of the cut, however, which lie adjacent the split portion of the shank piece and are designat-

ed 21 in the drawings, are not secured to the sole 10 of the shoe, but are raised to allow the lower layer 15 of the shank piece to be slipped under them and secured to the sole, 5 after which they are laid down over the said lower layer 15, the lining thus covering the side extensions 18 and 19 and the flaps 21 extending well toward the central line of the shoe and overlapping each other as shown in Fig. 1 of the drawings and glued or otherwise firmly secured in place.

The upper layer 16 of the shank piece is then brought down and secured in place. By this means the edges of the portion of the 15 lining behind the slit above referred to are secured entirely underneath the heel portion of the shank piece, but the portions in front of the cut and adjacent the split portion of the shank piece, are firmly held between the 20 upper and lower layers of the same, thereby neatly and completely covering the side extensions of the lower layer and at the same time having their own raw edges covered by the upper layer of the shank piece.

25 It will be understood, of course, that any suitable sock lining, inner sole, or other parts may be added as desired, but as the same form no part of the present invention they need not be here particularly described.

30 In Fig. 6 there is shown a portion of a modified form of shank piece, in which the same is split or formed of two pieces throughout its entire length, and the upper member of which is shown in the figure and designated 30.

In this case the construction of the other parts of the shoe would in general be the same as already above described, except that no cut as above referred to is required in the lining. The lining having been left partially unattached as above described, and the shoe having been turned if it be a turn shoe, the lining, in this modification of the invention, is raised and a shank member analogous to the lower part of the shank piece described 45 in the first embodiment of the invention, is secured in place. The edges of the lining are next secured in place over the same, and over them in turn is secured the member 30, and such other finishing steps taken as may 50 be desired, thus producing a somewhat similar general result to that of the first described embodiment.

Certain of the advantages of the invention have already been herein referred to. It 55 may be useful, however, to particularly allude at this point to the fact that a shoe constructed according to my invention will not only be of very good appearance inside, but will also be comfortable and beneficial to the foot, both 60 on account of the smooth, continuous and permanent manner in which the longitudinal arch-supporting extensions are covered and concealed by my improved form of lining, but also on account of the special form of the 65 shank piece itself, not only with regard to

supporting the longitudinal arch, but also in the support for the metatarsal arch. I have found that in practice a slight raising of the inside of the heel of the foot, has the effect of throwing the forward part of the foot 70 into a slightly differently tilted position which brings the same into a much more normal condition, and also that a support or pressure applied to the foot, not directly under but a little behind the metatarsal arch, 75 will tend to elevate this arch and also to prevent an unnatural, uncomfortable and harmful bunching together, or tendency to double under, of the toes of the foot. I have 80 therefore provided the carefully placed thickening near the forward end of the shank piece, which furnishes the above described assistance to the metatarsal arch and forward part of the foot and provided support at a point which in many high-heeled shoes is entirely unsupported, and co-operating with the same, I provide the slight thickening of the inner side of the heel, 17 of the shank piece, and in addition to the support provided for 85 the longitudinal arch of the foot.

I do not limit myself to the particular details of construction and method set forth in the foregoing specification and illustrated in the accompanying drawings, as the same refer to and set forth only certain embodiments of the invention and it is obvious that the same may be modified within the scope of the appended claim, without departing from the 90 spirit and scope of the invention.

Having thus described the invention, what is claimed as new and desired to be secured by Letters Patent, is as follows:

In a shoe, the combination with a sole and an upper comprising an outer member and a lining secured thereto; of a shank piece comprising a piece of material split throughout a portion of its length into an upper and a lower layer, said lower layer having a laterally and upwardly projecting portion; said lining having a cut extending upwardly from the lower edge thereof at a point intermediate the ends of said shank piece, a portion of said lining being secured between the layers of said shank piece and another portion being secured below said shank piece.

In witness whereof I have hereunto signed my name this 3d day of December, 1928.

ALEXANDER M. KESSLER.
